Sanford Kent, Jehiel H. Lehman, and Doris R. Lippman, Los Angeles, Calif., assignors to Power Tool Rentals, Inc., Los Angeles, Calif., a corporation of California

Application January 20, 1951, Serial No. 13,895

Term of patent 14 years

(Cl. D80—11)

To all whom it may concern:

Be it known that we, Sanford Kent, Jehiel H. Lehman, and Doris R. Lippman, residing in Los Angeles, county of Los Angeles, State of California, have invented a new, original, and ornamental Design for a Portable Tool Cabinet or Similar Article, of which the following is a specification, reference being had to the accompanying drawing, forming part thereof.

Fig. 1 is a perspective view of a portable tool cabinet or similar article showing our new design.

Fig. 2 is a top plan view thereof.

Fig. 3 is an end elevational view thereof.

The dominant features of our design reside in the portions shown in full lines.

We claim:

The ornamental design for a portable tool cabinet or similar article, substantially as shown and described.

SANFORD KENT.
JEHIEL H. LEHMAN.
DORIS R. LIPPMAN.
